UNITED STATES PATENT OFFICE.

JAMES STEPHEN LUCKETT AND CLYDE CAMERON LIVESAY, OF TORONTO, ONTARIO,
CANADA.

DESK-TRAY.

1,386,717.

Specification of Letters Patent.

Patented Aug. 9, 1921.

Application filed October 4, 1920. Serial No. 414,635.

To all whom it may concern:

Be it known that we, JAMES STEPHEN LUCKETT, manufacturer, and CLYDE CAMERON LIVESAY, salesman, both citizens of the 5 United States, residing at Toronto, in the county of York, Province of Ontario, Canada, have invented certain new and useful Improvements in Desk-Trays, of which the following is the specification.

Our invention relates to improvements in 10 desk trays and the object of the invention is to devise a tray for compactly holding various kinds of paper such as are used by stenographers so that they will be separately held, and in which the tray may be readily 15 adjusted to separate the various kinds of paper apart and in such a way that a single sheet of any of the various kinds may be readily picked up by the operator and it consists 20 essentially of the arrangement and construction of parts as hereinafter more particularly explained.

Figure 1 is a perspective view of our desk tray.

Fig. 2 is a cross sectional view showing 25 the tray in the closed position, ready either for insertion in a drawer or so that a cover may be slipped thereover.

Fig. 3 is a similar view to Fig. 2 showing 30 the parts adjusted so as to separate the various kinds of paper.

Fig. 4 is a longitudinal sectional view through Fig. 2.

Fig. 5 is a detail view of a portion of one 35 of the side walls of the main tray showing the curved grooves therein.

Fig. 6 is a detail of the slotted plate for 40 adjustably holding the trays.

In the drawings like characters of reference 45 indicate the corresponding parts in each figure.

1 indicates the main or outer tray, the side walls 2 and 3 of which are provided with curved grooves 4. 5 are plates provided with 45 curved slots 6 corresponding in shape to the grooves 4 and coinciding therewith. The upper ends of the slot 6 are provided with depressions 7 the purpose of which will hereinafter appear. 8 and 9 are supplemental 50 trays which are provided with inclined rear walls 10 forming a back tray portion which is in the form of an acute angle and into which piles of paper 11 and 12 fit.

By this means the front edges of the paper 55 are inclined outwardly into a position so that

the upper sheet of paper can always be readily separated from the pile by the fingers of the operator. 13 are plates which are rigidly secured to the lower supplemental tray 8 and extends upwardly therefrom at 60 each side of the upper supplemental tray 9. The plates 13 are provided with orifices 14 which are located just above the upper angle between the top and inclined back wall of the lower supplemental tray 8. 15 are pins 65 which extend outward from the upper supplemental tray between the orifices 14. By this means the upper and lower supplemental trays are hingedly connected together. 16 are pins which extend out from 70 each end of the supplemental tray 8 into the curved slots 6 and grooves 4 and normally rest on the bottom of such slots and grooves. When the lower supplemental tray is lifted so as to carry the pin 16 upward through the 75 grooves and slots, the back ends of the supplemental trays engage with back of the main tray 1 and are held in the position shown in Fig. 3, the pins 16 dropping into the depressions 7 thereby holding the supplemental trays 8 and 9 in the position 80 shown in Fig. 3.

In this position it will readily be seen that any sheet of paper required by the operator may be readily and quickly picked out without 85 any fumbling or mixing of the paper as often takes place when the paper is loosely held in the drawer. If desired the lower portion of the main tray may be sufficiently deep and divided up so as to hold the various 90 kinds of envelops required.

What we claim as our invention is.

1. In a desk tray, a main tray having a bottom and back wall extending at an angle to each other, a plurality of supplemental 95 trays extending radially from the apex of the angle formed by the bottom and back wall of the main tray, and means for supporting the supplemental trays within the main tray whereby the bottom of the lowermost tray extends at an angle to the bottom of the main tray and the back portions of the supplemental trays together fit the space intervening between the bottom of the lowermost supplemental tray and the back wall 100 of the main tray and arranged in sectoral form.

2. A desk tray comprising a main tray, a plurality of supplemental trays having their back walls inclined inwardly toward the top, 110

means for connecting the trays together whereby when the lowermost tray is raised to an inclined position the uppermost tray bears against the back of the main tray so as to support the bottom thereof on the inclined back wall of the underlying tray, and means for supporting the underlying tray in an inclined position.

3. A desk tray, comprising a main tray

having curved slots in the side walls thereof, 10 a plurality of supplemental trays having inwardly inclined back walls, a hinged connection between the rear portions of the supplemental trays, and pins extending laterally from the lowermost supplemental tray into 15 the curved slots of the main tray.

JAMES STEPHEN LUCKETT.
CLYDE CAMERON LIVESAY.
